ROBERT MIEHLE, OF CHICAGO, ILLINOIS.

TRIP-CONTROL MECHANISM FOR PRINTING-PRESSES.

1,302,693.

Specification of Letters Patent.

Patented May 6, 1919.

Application filed November 5, 1917. Serial No. 200,376.

To all whom it may concern:

Be it known that I, ROBERT MIEHLE, a citizen of the United States, residing at Chicago, in the county of Cook and State of Illinois, have invented a certain new and useful Improvement in Trip-Control Mechanisms for Printing-Presses, of which the following is a clear, concise, and exact description, reference being had to the accompanying drawings, forming a part of this specification.

My invention relates to trip control mechanism for printing presses and has for its general object to provide means for controlling the trip mechanism which minimizes mental effort required in tripping a machine during a given cycle.

In the present state of the art it is the practice to employ press operated means for tripping the press, and to provide positioning means, which is generally manually actuated, to position the press driven means to trip the machine. In tripping mechanisms of this character the positioning means is effective to position the press driven tripping means only during a short period in the cycle of the machine. Thus, if the positioning means is moved to tripping position at any other period in that cycle of the machine, and is moved from its tripping position before the tripping mechanism assumes a position in which said positioning means is effective to trip the mechanism, the machine will not trip. And, if the positioning means is moved to tripping position, and is held there more than a cycle of the machine it is liable to trip the machine twice where it was the intention of the operator to trip the same but once. As a result, the operator must constantly watch the machine so that he does not move the positioning means to tripping position too early and that he does not release the same too late. In order that the operator may be relieved of a great portion of this mental effort, while tripping the machine, I provide mechanism whereby the positioning means of the tripping mechanism can only be moved to tripping position during that period in which said positioning means is actually effective to position the press driven tripping mechanism, and I further provide means for moving said positioning means to its

normal untripping position immediately after the movement of said positioning means to tripping position has become effective upon the tripping mechanism. I also provide means, which may be attached or detached at the will of the operator from the positioning means, whereby said positioning means will be automatically moved to tripping position at the proper time to trip the machine during each cycle thereof so that the machine may be tripped for a succession of cycles without requiring the operator to move the positioning means to tripping position during each cycle.

A further object of my invention resides in providing means whereby the above described mechanism may be utilized in tripping a two couple machine. In machines of the two couple type, it is common to employ press driven timing means for positioning the trip positioning means of the second couple, said press driven timing means serving to position said trip positioning means of the second couple at a time when the same will be effective to position said tripping mechanism to trip the second couple, and in conjunction with the press driven timing means a coupling means is employed which may be moved to render said press driven timing means effective upon the trip positioning means of said second couple, said coupling means being controlled by a foot treadle which may be moved to position said coupling means to render said press driven timing means effective upon said trip positioning means of the second couple at a time previous to that time in which the press timing means moves said trip positioning means of said second couple into tripping position. The timing of the several couples is such that, in order that a sheet may be tripped so that it is not printed upon by both couples as it passes through the machine, the trip positioning means of the first couple should be positioned to trip the first couple at a time previous to the time in which the trip positioning means of the second couple should be moved to tripping position to trip the second couple as the sheet passes through the machine. It is common to arrange the trip positioning means of both couples so that the operator may operate both, to move the same to tripping po-

sition at the same time by pushing down upon one treadle. In tripping a machine of this character the operator must see to it that he depresses the treadle after the trip 5 positioning means of the second couple has become ineffective to trip said second couple relatively to the last sheet passing through the machine, and as above stated before the trip positioning means of the 10 first couple is effective to trip that couple relative to the sheet which he desires to be tripped. My invention renders it unnecessary that the operator see to it that he exerts pressure upon the treadle only during 15 the above mentioned period. In accomplishing this I provide means, in addition to the trip positioning timing means, as above described, whereby said coupling means of the trip positioning means of the 20 second couple is moved into operative relation with said press driven trip positioning means of the second couple simultaneously with the movement of the trip positioning means of the first couple into tripping position. And it will be noted further that by 25 providing press driven timing means for the trip positioning means of the first couple which is adapted to move said trip positioning means of the first couple into untripping position immediately after the 30 same has been effective to trip the first couple that the operator cannot inadvertently trip the first couple on the succeeding sheet by keeping the treadle depressed too long. 35 Thus it will be noted that the operator need only see to it that he exerts pressure upon the treadle at any time during the preceding cycle of the first couple to trip the sheet providing he maintains pressure thereon 40 until the press driven timing means of the trip positioning means of the first couple allows said trip positioning means to be moved to tripped position. In order that the operator may trip the machine at the 45 latest time possible, whereby he may have as much time as the necessary arrangement of the machine may allow, I time the above noted press driven timing means so that said press driven timing means allows the 50 treadle to be depressed just after the grippers of the first cylinder would take the fed sheet, the tripping mechanism of the first cylinder being so arranged that this cylinder is tripped between that point and the 55 point where the grippers would engage the leading edge of the fed sheet with the form as is the usual case.

With these and other objects in view which will be hereinafter fully described 60 and particularly pointed out in the claims the invention resides in the mechanism illustrated in the accompanying drawings forming a part of this specification and disclosing the preferred embodiment thereof, in 65 which:

Figure 1 is a partial side elevation of a printing press in which are incorporated the features of my invention.

Fig. 2 is a section in front elevation on the line 2—2 of Fig. 1.

Fig. 3 is a partial side elevation of a printing press showing my invention as applied to a tripping mechanism similar to that disclosed in my United States Patent, No. 1,081,320, granted Dec. 16, 1913.

Fig. 4 is an enlarged section in plan elevation on the line 4—4 of Fig. 1.

Fig. 5 is a partial side elevation of a portion of the mechanism showing the same in a different position than that illustrated in Fig. 1.

Fig. 6 is a similar view with the parts in a different position.

Fig. 7 is an enlarged partial top plan view of a portion of the mechanism as illustrated in Fig. 3.

Fig. 8 is a partial side elevation of a portion of the mechanism illustrated in Fig. 3 showing the same in different position.

Like characters of reference indicate like parts in the various views.

While I have illustrated the invention as applied to a two couple machine it will be obvious that from the following description the invention may be used upon a single couple machine with equal advantage.

In the drawings 1 designates the frame of the machine in which is journaled the first impression cylinder 2, the transfer cylinder 3, and the second impression cylinder 4. The impression cylinder 2 rotates in a counter clockwise direction, the transfer cylinder 3 rotates in a clockwise direction, the impression cylinder 4 rotates in a counter clockwise direction. The bed 5, which carries a form 6 for the first impression cylinder 2 and a form 7 for the second impression cylinder 4 is reciprocated in unison with said cylinder. A cylinder 2 is provided with grippers 8 which are adapted to take a sheet from a feed-board 9, bring the same in impression relation with the form 6, and to then transfer the sheet to the grippers 10 of the transfer cylinder 3 which transfer the sheet to the grippers 11 of the cylinder 4 which takes the sheet and brings the same into impression relation with the form 7 after which said grippers release the sheet upon a delivery apparatus not shown as is the usual practice.

The impression cylinders 2 and 4 are adapted for movement transversely of their axes to move the same into and out of printing relation with their respective forms, the same being journaled in boxes 12 which are slidably mounted in guide ways 13 of the press frame 1. These boxes 12 are provided with springs 14 which are adapted to move said boxes to position the impression cylinders in their nonimpression or tripped posi-

tion. The boxes 12 are also provided with eccentric mechanisms 15 of usual construction whereby the impression cylinders may be moved into impression relation with 5 their respective forms against the influence of the springs 14, said eccentric mechanism being provided with actuating arms 16 whereby the same may be moved.

The tripping mechanism as shown is of 10 usual construction and is fully described in the United States Patent, No. 1,081,820 granted to me Dec. 16, 1913, and needs but a cursory description in order that this invention may be fully understood. A cam shaft 15 17 is journaled in the press frame and is driven from the press mechanism and makes one complete revolution for each cycle of the machine. A rock shaft 18 is journaled in the press frame and has a cam arm 19 af- 20 fixed thereto, which is provided with a friction roller which is engaged with the groove of a cam 20 mounted upon said cam shaft 17. The cam arm 19 is rotatably mounted upon said rock shaft 18 and carries a hook 25 21 fixedly mounted at its outer end, which is adapted to engage the tooth 22 fixedly mounted upon said rock shaft 18. Arms 23 are mounted upon said rock shaft 18 on either side of the machine and are connected 30 with their respective actuating arms 16 through connecting links 24, and the eccentric mechanisms 15 are actuated to move the impression cylinder into and out of impression position by the cam 20 acting through 35 the cam arm 19, hook 21, tooth 22, arm 23, and the connecting links 24 which are connected to said actuating arms 16. The hook 21 is pivotally mounted upon the cam arm 19 and is adapted to be moved out of engage- 40 ment with the tooth 22. A roller 25 is mounted upon the hook 21 near the free end thereof and travels in the groove of a cam lever 26 which is fixedly mounted upon a rock shaft 27 journaled in the press frame. The 45 upwardly facing surface of the cam groove of the cam lever 26 is provided with a raised portion 28, which lies below the roller 25 when the roller of the cam arm 19 is passing through the arc *a b* of the cam 20, the 50 mechanism being so arranged that when said roller of the cam arm 19 is passing through said arc *a b* the impression cylinder is in its upper or tripped position. If the cam lever 26 is raised, while the parts are 55 in this position, the raised portion 28 en- gages the roller 25 to lift the hook 21 out of engagement with the tooth 22, thus dis- connecting the cam arm 19 from the eccentric mechanisms 15 whereby the cylinder re- 60 mains in its upper or tripped position dur- ing the succeeding revolution of said cam 20. If the cam lever 26 is released during 65 the time that the roller of the cam arm 19 is passing through that portion of the groove of the cam 20 which lies in the arc *b c, c d*,

and *d a*, said cam lever and hook 21 are sup- 70 ported by the engagement of the under sur- face of the hook, which lies between the hook portion thereof and the roller of the cam arm 19, with the crown of the tooth 22, the tooth receiving portion of said hook having passed out of engaging relation with 75 said tooth during the initial movement of the roller of cam arm 19 through the arc *b c*. If said cam lever 26 is released during 80 said period the hook reengages the tooth as said roller of cam arm 19 passes through the arc *a b* after having passed through said arc *d a*, whereupon the normal position of the parts is again resumed. It will be noted 85 that, while the roller of the cam arm 19 is passing through the arc *c d* that the cylinder is in impression relation with its form.

Fixedly mounted upon the rock shaft 27 90 is a lever 29, and a tension spring 30 has its opposite ends connected to said lever 29 on the press frame to normally maintain the downwardly facing surface of the cam groove of the cam lever 26 against the roller 25. A push rod 31 has its lower end pivotally 95 connected to the outer end of the lever 29 and extends upwardly through the foot board 32 which is supported on the main frame. A cam 33 is mounted upon the cam shaft 17, and a lever 34 is fixedly mounted 100 upon said rock shaft 27 and has a friction roller 35 mounted upon the outer end thereof and adapted to engage said cam 33. The cam 33 has a high portion 36 and a low portion 37, the low portion 37 being rela- 105 tively short and being disposed to engage said roller 35 when the roller of the cam arm 19 is in the arch *a b* and is just about to enter the arc *b c* of the cam 20. It will be noted at this point that, due to the fact that the raised portion 28 of the cam lever 26 is 110 relatively short said cam lever 26 can only operate to lift the hook 21 out of engagement with the tooth 22 when the roller of the cam arm 19 is in the arc *a b*, and that the rais- 115 ing of said cam lever 26, or the moving of the same to tripping position, is only effective to actually trip the press as the roller of the cam arm 19 is entering the arc *b c*, that is, there is but one point in the cycle of the ma- 120 chine, and that is a relatively short period, in which the movement of said cam lever 26 into tripping position is effective to position the part of the tripping mechanism to actually trip the cylinder. Thus, regardless of how long the cam lever has been held in 125 its raised or tripping position the mechanism will not trip unless said cam lever is held in its tripping position at the proper time. In tripping a machine provided with my invention the operator may press down upon the push rod 31, which is provided with an enlarged treadle portion 38, at any time during the cycle of the machine. How- ever the cam 33 will prevent said push rod 130

31 from moving downwardly to raise the cam lever 26 until just before the mechanism has reached that position in which the raising of said cam lever 26 into tripping position will be effective to trip the machine. In this way the operator is notified that he has in fact tripped the mechanism by the raising of said cam lever. Following the actual tripping of the mechanism the 10 cam 33 actuates the lever 34 to move the cam lever 26 and its connected parts back to untripping position whereby the operator is notified that he has held the cam lever in tripping position long enough to trip the machine for that cycle whereby he is prevented from inadvertently maintaining the cam lever 26 in its raised or tripping position and the machine is prevented from tripping twice where the operator intended the 15 same to trip but once.

The treadle portion 38 of the push rod 31 passes through an enlarged hole 39 in the foot board 32 whereby the same is allowed to be moved laterally. A pivot bracket 40 25 is secured upon the under side of the foot board 32 and an actuating lever 41 is pivotally mounted thereon. One arm of the actuating lever 41 extends toward the push rod 31 and a compression spring 42 is disposed between 30 said foot board and said arm and serves to maintain said arm in its lower position, the ends of the spring 42 being received within recesses of the foot board and said actuating lever where said spring is maintained in 35 proper position. A second arm 43 extends outwardly from the other side of the pivotal point of the actuating lever 41 and abuts the pivot bracket 40 and limits the downward movement of the other side of said actuating lever. A latch dog 43 is pivoted to the 40 push rod 31 at 44 and is adapted to move toward and away from the outer end of the adjacent arm of the actuating lever 41. Said latch dog 43 is provided with a stop 45 which engages the push rod 31 when said latch dog is in its position nearest adjacent said actuating lever 41, and a compression spring 43' is disposed between said latch dog and the push rod 31 and serves to maintain 50 the same in its outer position, said compression spring having the opposite ends thereof engaging recesses in the push rod 31 and said latch dog to maintain the same in proper position. The push rod 31 is inclined away from the actuating lever 41 and the upper end thereof normally rests against the side of the hole 39 opposite said actuating lever. In this position the latch dog 43 is disposed to one side of the outer 55 end of the adjacent arm of the actuating lever 41 whereby said push rod may move up and down longitudinally without interference from said actuating lever. The latch dog 43 is provided with an upwardly facing 60 surface 46, and the actuating lever 41 is pro-

vided with a downwardly facing surface 47. The surfaces 46 and 47 are so disposed that when the push rod 31 is moved to tripping position and is then moved laterally toward said actuating lever, the hole 39 being large 70 enough to permit this, the surface 46 lies below surface 47. If the push rod 31 is allowed to raise while in this lateral position said surface 46 engages said surface 47 and the force of the spring 42 is exerted 75 upon said push rod to move the same downwardly. The strength of the spring 42 is relatively greater than the strength of the spring 30 whereby the roller 35 of the lever 34 is maintained in constant engagement 80 with the cam 33. Inasmuch as the low portion 37 of the cam 33 passes over the roller 35 when the tripping mechanism is in such position that the raising of the cam lever 26 to tripping position will be effective to trip 85 the machine, the machine will be tripped constantly when said actuating lever is in engagement with said latch dog. The surface 46 is inclined downwardly and away from the actuating lever, and the surface 47 90 is inclined downwardly toward said latch dog whereby said actuating lever and latch dog cannot work out of engagement as said push rod is moved upwardly and downwardly. By reason of the fact that the 95 latch dog may be moved toward the push rod 31 against the influence of the spring 43' the push rod 31 may be moved toward the actuating lever at any time, thus allowing said push rod to be moved toward said actuating lever and downwardly simultaneously. Fig. 5 shows the position of the actuating lever, latch dog and push rod when said latch dog is in engagement with said actuating lever, and the roller 35 is 100 passing under the low portion 37 of the cam 33. Fig. 6 shows the position of the actuating lever, latch dog and push rod when said actuating lever and latch dog are in engagement and the roller 35 is passing over the 105 high portion 36 of the cam 33.

As before noted Fig. 1 shows a two couple printing machine to which my present invention has been applied. The mechanism which actuates the tripping mechanism of 115 the second couple needs no description for the perfect understanding of the present invention and is fully disclosed in my United States application, Serial No. 161,700, filed April 13, 1917.

Figs. 3, 7 and 8 show my invention as applied to a two couple printing machine having tripping mechanism similar to that disclosed in the United States Patent No. 1,081,320, granted to me Dec. 16, 1913. The 125 machine shown in Figs. 1 and 3 are generally similar in structure and similar reference characters are given to the similar parts in the different figures. The only difference between these machines lies in the 130

mechanism for positioning the tripping mechanism for the second couple. It will be noted that as herein disclosed and as disclosed in the above noted patent the trip 5 positioning of the second couple is manually positioned in the following manner. The trip positioning cam of the second couple, which is similar to the cam lever 26 as above described is fixedly mounted upon a rock 10 shaft similar to rock shaft 27, as above described, and a lever 48 is affixed to said rock shaft in a manner similar to the way in which the lever 29 is affixed to the rock shaft 27 as above described. The outer end 15 of the lever 48 is disposed adjacent the cam shaft 17 and has a friction roller 49 mounted thereon for rotation and for lateral movement along the axis thereof. A cam 50 is fixedly mounted upon said cam shaft 17, and 20 a tension spring 51 has the opposite ends thereof fixed to said lever 48 and the press frame and is adapted to move said lever 48 toward the cam 50, a stop 52 being provided to limit this movement of the lever 48 25 so that the roller 49 is just out of contact with the low portion of the cam 50. The cam 50 is provided with a high portion 53 which is so timed as to move the lever 48 downwardly when the cam lever which is 30 affixed thereto is effective to trip its respective tripping mechanism. As before stated the roller 49 is movable laterally in the direction of its axis, and it is adapted to be moved into or out of the path of said cam 35 50. A bell crank lever 54 is pivotally mounted upon a bracket of the press frame and has one arm thereof extending upwardly and adapted to engage a stud of said friction roller 49. The rock shaft 27 40 of Fig. 3 is provided with a second bell crank lever 55, which is rotatably mounted thereon and has a flexible rod 56 extending therefrom, the outer end of said rod underlying a horizontally disposed arm of the 45 bell crank lever 54. A tension spring 57 has its opposite ends connected to said lever 55 and the press frame and tends to move said bell crank lever 55 in a counter clockwise direction, with said rod 56 out 50 of engagement with the bell crank lever 54. A push rod 58 is pivotally connected to the outer end of the horizontally extending arm of the bell crank lever 55 and extends upwardly through a hole 59 in the foot board 55 32, and the parts are so arranged that when the push rod 58 is pushed downwardly the bell crank lever 54 is actuated to push the roller 49 into the path of the cam 50. The cam shaft 17 rotates in a counter clockwise 60 direction and a face cam 60 is formed integral with the cam 50 just beyond the trailing portion of the high portion 53 and is adapted to push the friction roller 49 out of the path of said cam 50 as said face 65 cam 60 passes by the roller. As before

noted this mechanism is fully described in the above noted patent and needs no further description or disclosure herein to fully describe this invention.

The push rod 58 is provided with a treadle portion 61 for the convenient manipulation thereof. Said treadle portion is provided with an extension member 62 which has an upwardly facing surface adapted to underlie a downwardly facing surface 63 formed upon the treadle portion 38 of the push rod 31. The push rod 31, the actuating lever 41, and the latch dog 43 and their correlated parts have the same relation to each other in Fig. 3 as hereinbefore described relative to Fig. 1. The hole 59 through which the push rod 58 passes is enlarged and allows lateral movement of said push rod, and has a connecting portion leading to the hole 39, through which the push rod 31 passes, said extension member 62 working in this connecting portion. The arrangement is such that the extension member 62 may be maintained so that the upwardly facing surface thereof underlies the downwardly facing surface 63 during all the lateral positions of the push rod 31 and said push rod 58 may be moved away from said push rod 31 so that said opposing surfaces do not overlap. A locking member 64 is secured to the upper surface of the foot board 32 and has an undercut portion 65 which is adapted to be engaged by the treadle portion 61 when said push rod 58 is in its lower position whereby the tripping mechanism of the second cylinder may be set to trip said cylinder during a number of consecutive cycles, see Fig. 8. A flat spring member 66 is secured upon the locking member 64 and its free end extends therefrom toward said push rod 58, and is so disposed that the treadle portion 61 may be engaged to prevent the push rod 58 from moving toward the push rod 31. The locking member 64 and the spring member 66 100 are so disposed that when the treadle portion 61 of the push rod 58 is engaged with either one of said members the upwardly facing surface of the extension member 62 and the downwardly facing surface 63 of 105 the treadle portion 38 of the push rod 31 do not overlap. Thus the tripping mechanism of the second cylinder may be maintained out of the control of the trip positioning mechanism of the first cylinder and 110 the same may be maintained out of such relation in either its untripping relation or its tripping position.

Fig. 7 shows the treadle portion 61 of the push rod 58 in engagement with the spring 125 member 66 as above described.

It will be noted that by the above described mechanism the operator is enabled to determine the proper time when the positioning means of the tripping mechanism 130

should be moved to tripping position in order to trip the cylinder. In fact he is prevented from either tripping too soon, which might otherwise result in the machine being tripped in the cycle before the one in which he intended to trip the machine, or maintaining the trip positioning mechanism in tripping position too long whereby the machine might be tripped in the cycle succeeding the cycle in which he intended to trip the machine. Thus, it is only necessary that the operator see to it that the pressure is applied to the push rod 31 as the roller passes over the low portion and until it again regains the high portion of the cam 33. After the machine has been tripped the roller 35 regains the high portion of the cam 33 and the push rod 31 is moved upwardly whereby the operator is notified by the sensation of the impulse imparting to the trip positioning means by the cam that the machine has been tripped.

A balance weight 67 is affixed to the push rod 58 and serves to maintain said push rod in such a position that the downwardly facing surface 63 and the upwardly facing surface of the extension member 62 overlap one another. I have provided a treadle 68 which is affixed to the arm 43 of the actuating lever 41 whereby the operator may raise the opposite arm of said actuating lever at any time to engage the same with the push rod 31 without necessitating the movement of said push rod to its lower or tripping position.

While I have shown my invention in connection with a two couple printing machine, it will be noted that Fig. 1 shows the same in connection with the first couple of a two couple machine, the means for tripping the second couple being entirely independent of the means for tripping the first couple, which means it will be noted embodies the main features of my invention, wherefore it is obvious that the invention may be used upon either two couple or a single couple machine without changing even the structural details of the same.

While I have herein shown and particularly described the preferred embodiment of my invention I do not wish to be limited to the precise details of construction shown as changes may be readily made without departing from the spirit of my invention, but having thus described my invention I claim as new and desire to secure by Letters Patent the following:—

1. A printing press including a tripping mechanism, trip positioning means in operative relation therewith and including resilient means adapted to cause said trip positioning means to assume untripping position, and timed press driven means in operative relation with said trip positioning means and adapted to move the same into

untripping position after said positioning means has been moved into tripping position and has effected the positioning of said tripping mechanism to trip.

2. A printing press including a tripping mechanism, trip positioning means in operative relation therewith and including resilient means adapted to cause said trip positioning means to assume untripping position, and timed press driven means in operative relation with said trip positioning means and adapted to prevent said positioning means from being moved to tripping position until such time when such movement will be effective to position said tripping mechanism to trip, and adapted to move said positioning means into untripping position after said positioning means has been moved into tripping position and has effected the positioning of said tripping mechanism to trip.

3. A printing press including a tripping mechanism, trip positioning means in operative relation therewith for controlling the same and adapted to normally assume untripping position, timed press driven means in operative relation with said trip positioning means, and adapted to move the same into untripping position after said positioning means has been moved into tripping position and has effected the positioning of said tripping mechanism to trip, and yieldable detachable means adapted to be engaged with said trip positioning means to overpower the normal tendency thereof and adapted to move the same to tripping position.

4. A printing press including a tripping mechanism, trip positioning means in operative relation therewith for controlling the same and adapted to normally assume untripping position, timed press driven means in operative relation with said trip positioning means and adapted to prevent said positioning means from being moved to tripping position until such movement will be effective to position said tripping mechanism to trip and adapted to move said positioning means into untripping position after said positioning means has been moved into tripping position and has effected the positioning of said tripping mechanism to trip, and yieldable detachable means adapted to be engaged with said trip positioning means to overpower the normal tendency thereof and adapted to move the same to tripping position.

5. A printing press including two printing couples, a tripping mechanism in operative relation with each couple, a trip positioning means for one of said tripping mechanisms and adapted to normally assume untripping position, timed press driven means in operative relation with said trip positioning means, and adapted to move the same into untripping position after said positioning means

- has been moved into tripping position and has effected the positioning of its tripping mechanism to trip, a second trip positioning means for the other tripping mechanism, and 5 means whereby the movement of said first mentioned trip positioning means into tripping position operates to cause said second trip positioning means to position its tripping mechanism to trip.
- 10 6. A printing press including two printing couples, a tripping mechanism in operative relation with each couple, a trip positioning means for one of said tripping mechanisms and adapted to normally assume untripping 70 position, timed press driven means in operative relation with said trip positioning means and adapted to prevent said positioning means from being moved to tripping position until such time when such movement will be 75 effective to position said one tripping mechanism to trip and adapted to move said positioning means into untripping position after said positioning means has been moved into tripping position and has effected the positioning 80 of said tripping mechanism to trip, a second trip positioning means for the other tripping mechanism, and means whereby the movement of said first mentioned trip positioning means into tripping position operates to cause said second trip positioning means to position its tripping mechanism to trip.
- 15 7. A printing press including two printing couples, a tripping mechanism in operative relation with each couple, a trip positioning means for one of said tripping mechanisms and adapted to normally assume untripping 85 position, timed press driven means in operative relation with said trip positioning means, and adapted to move the same into tripping position after said positioning means has been moved into tripping position and has effected the positioning of its tripping mechanism to trip, a second trip positioning means for the other tripping mechanism, and means whereby the movement of said first mentioned trip positioning means into tripping position operates to cause said second trip positioning means to position its tripping mechanism to trip, and detachable 90 yieldable means adapted to be engaged with said first mentioned trip positioning means to overpower the normal tendency thereof and adapted to move the same to tripping position.
- 20 8. A printing press including two printing couples, a tripping mechanism in operative relation with each couple, a trip positioning means for one of said tripping mechanisms and adapted to normally assume untripping 95 position, timed press driven means in operative relation with said trip positioning means, and adapted to move the same into tripping position after said positioning means has been moved to tripping position and after such movement has effected the positioning of said tripping mechanism to trip said movable element of 100 that couple, and a connecting element between said positioning means of the several couples whereby said positioning means of the other couple is moved to tripping position when said one positioning means is so moved.
- 25 9. A printing press including two printing couples, each printing couple including a movable element adapted to be moved into and out of printing relation with its complementary printing element, a tripping mechanism for each of said couples in operative relation with its respective movable element, a positioning means for each tripping mechanism in operative relation with its respective 105 tripping mechanism, a press driven timing means in operative relation with the positioning means of one of said tripping mechanisms, and adapted to move said positioning means into untripping position after said positioning means has been moved to tripping position and after such movement has effected the positioning of said tripping mechanism to trip said movable element of that couple, and a connecting element between said positioning means of the several couples whereby said positioning means of the other couple is moved to tripping position when said one positioning means is so moved.
- 30 10. A printing press including two printing couples, each printing couple including a movable element adapted to be moved into and out of printing relation with its complementary printing element, a tripping mechanism for each of said couples in operative relation with its respective movable element, a positioning means for each tripping mechanism in operative relation with its respective 110 tripping mechanism, a press driven timing means in operative relation with the positioning means of one of said tripping mechanisms, and adapted to time the movement of said positioning means into tripping position and to move said positioning means into untripping position after the movement of said positioning means has effected the positioning of said tripping mechanism to trip said movable element and a connecting element between said positioning means of the several couples whereby said positioning means of the other couple is moved to tripping position when said one positioning means is so moved.

- ing couples, each printing couple including a movable element adapted to be moved into and out of printing relation with its complementary printing element, a tripping mechanism for each of said couples in operative relation with its respective movable element, a positioning means for each tripping mechanism in operative relation with its respective tripping mechanism, a press driven timing means in operative relation with the positioning means of one of said tripping mechanisms, and adapted to prevent said positioning means from being moved to tripping position until such time 15 when such movement will be effective to position said tripping mechanism to trip said movable element of that couple, a connecting element between said positioning means of the several couples whereby said positioning 20 means of the other couple is moved to tripping position when said one positioning means is so moved, and detachable yieldable means for moving said positioning means of said one couple into tripping position.
12. A printing press including two printing couples each printing couple including a movable element adapted to be moved into and out of printing relation with its complementary printing element, a tripping mechanism 25 for each of said couples in operative relation with its respective movable element, a positioning means for each tripping mechanism in operative relation with its respective tripping mechanism, a press driven timing means in operative relation with the positioning means of one of said tripping mechanisms and adapted to move said positioning means into untripping position after said positioning means has been moved 30 to tripping position and after such movement has effected the positioning of said tripping mechanism to trip said movable element of that couple, a connecting element between said positioning means of the several couples whereby said positioning means of the other couple is moved to tripping position when said one positioning means is so moved, and detachable yieldable means for moving said positioning means of said one couple into tripping position.
13. A printing press including two printing couples, each printing couple including a movable element adapted to be moved into and out of printing relation with its complementary printing element, a tripping mechanism for each of said couples in operative relation with its respective movable element, a positioning means for each tripping mechanism in operative relation with 45 its respective tripping mechanism, a press driven timing means in operative relation with the positioning means of one of said tripping mechanisms, adapted to time the movement of said positioning means into tripping position and to move said position- 50
- ing means into untripping position after the movement of said positioning means has effected the positioning of said tripping mechanism to trip said movable element, a connecting element between said positioning 55 means of the several couples whereby said positioning means of the other couple is moved to tripping position when said one positioning means is so moved, and detachable yieldable means for moving said positioning means of said one couple into tripping position.
14. A foot control comprising a longitudinally movable push rod adapted for limited lateral movement, yieldable means for normally maintaining the same at one end of its longitudinal movement, said push rod having a surface facing in the direction of its normal position, and yieldable actuating means adapted to exert influence in a direction opposed to the direction of influence of said first mentioned yieldable means and having a relatively greater force than said first mentioned yieldable means and having a surface opposing said first mentioned surface and disposed in the path thereof and engageable therewith when said push rod is moved to one position in its lateral movement.
15. A foot control comprising a longitudinally movable push rod adapted for limited lateral movement, yieldable means for normally maintaining the same at one end of its longitudinal movement, said push rod having a surface facing in the direction of 90 its normal position, said push rod also being provided with a surface facing in a direction opposite to said first mentioned surface, a second push rod adapted for limited longitudinal movement in a direction substantially parallel to the longitudinal movement of said first mentioned push rod and adapted for limited lateral movement and having a surface opposing said last mentioned surface and engageable therewith in all the lateral movements of said first mentioned push rod and disengageable therewith by the lateral movement of said second mentioned push rod, yieldable means for normally maintaining said second push rod at that 95 end of its long movement corresponding with the normal position of said first mentioned push rod, and yieldable actuating means adapted to exert influence in a direction opposed to the direction of influence of said first and second mentioned yieldable means and having a relatively greater force than the combined force of said first and second mentioned yieldable means and having a surface opposing said first mentioned 100 surface and disposed in the path thereof and engageable therewith when said push rod is moved to one position in its lateral movement.
16. A printing press including two print- 105

- ing couples operating sequentially in printing, each printing couple including a movable element adapted to be moved into and out of printing relation with its complementary printing element, a tripping mechanism for each of said couples in operative relation with its respective movable element, a positioning means for each tripping mechanism in operative relation with its 5 respective mechanism, a timed press driven actuating means included in the trip positioning means of the second couple adapted to move its trip positioning means to tripping position to trip said second couple, a 10 coupling means included in the trip positioning means of the second couple adapted to be moved to render said timed press driven actuating means operative relative to its trip positioning means, a press driven 15 timing means in operative relation with the positioning means of the first couple, and adapted to move said positioning means into untripping position after said positioning means has been moved to tripping position 20 25 and after such movement has effected the positioning of said tripping mechanism to trip said movable element of that couple, and a connecting element between said positioning means of the trip positioning 30 35 means of the first couple and said coupling means whereby said coupling means is moved to render said press driven actuating mean operative when said positioning means of the first couple is moved to tripping position.
17. A printing press including two printing couples operating sequentially in printing, each printing couple including a movable element adapted to be moved into and 40 out of printing relation with its complementary printing element, a tripping mechanism for each of said couples in operative relation with its respective movable element, a positioning means for each tripping mechanism 45 in operative relation with its respective tripping mechanism, a timed press driven actuating means included in the trip positioning means of the second couple adapted to move its trip positioning means 50 to tripping position to trip said second couple, a coupling means included in the trip positioning means of the second couple adapted to be moved to render said timed press driven actuating means operative relative 55 to its trip positioning means, a press driven timing means in operative relation with the positioning means of the first couple, and adapted to time the movement of said positioning means into tripping position 60 65 70 75 80 85 90 95 100 105 110 115 120 125 130
- trip positioning means of the first couple and said coupling means whereby said coupling means is moved to render said press driven actuating means operative when said positioning means is moved to tripping position.
18. A printing press including two printing couples operating sequentially in printing, each printing couple including a movable element adapted to be moved into and out of printing relation with its complementary printing element, a tripping mechanism for each of said couples in operative relation with its respective movable element, a positioning means for each tripping mechanism in operative relation with its respective tripping mechanism, a timed press driven actuating means included in the trip positioning means of the second couple adapted to move its trip positioning means to tripping position to trip said second couple, a coupling means included in the trip positioning means of the second couple adapted to be moved to render said timed press driven actuating means operative relative to its trip positioning means, a press driven timing means in operative relation with the positioning means of the first couple and adapted to move said positioning means into untripping position after said positioning means has been moved to tripping position and after such movement has effected the positioning of said tripping mechanism to trip said movable element of that couple, a connecting element between said positioning means of the trip positioning means of the first couple and said coupling means whereby said coupling means is moved to render said press driven actuating means operative when said positioning means is moved to tripping position, and detachable yieldable means for moving said positioning means of said first couple into tripping position.
19. A printing press including two printing couples operating sequentially in printing, each printing couple including a movable element adapted to be moved into and out of printing relation with its complementary printing element, a tripping mechanism for each of said couples in operative relation with its respective movable element, a positioning means for each tripping mechanism in operative relation with its respective tripping mechanism, a timed press driven actuating means included in the trip positioning means of the second couple adapted to move its trip positioning means to tripping position to trip said second couple, a coupling means included in the trip positioning means of the second couple adapted to be moved to render said timed press driven actuating means operative relative to its trip positioning means, a press driven timing means in operative relation with the positioning means of the first couple and adapted to move said positioning means into untripping position after the movement of said positioning means has effected the positioning of said tripping mechanism to trip said movable element and a connecting element between said positioning means of the

means of the first couple, adapted to time the movement of said positioning means into tripping position and to move said positioning means into untripping position after 5 the movement of said positioning means has effected the positioning of said tripping mechanism to trip said movable element, a connecting element between said positioning means of the trip positioning means of the 10 first couple and said coupling means where-

by said coupling means is moved to render said press driven actuating means operative when said positioning means is moved to tripping position, and detachable yieldable means for moving said positioning means of 15 said first couple into tripping position.

In testimony whereof, I affix my signature this 3rd day of November, A. D. 1917.

ROBERT MIEHLE.
